CLAIM

I claim the ornamental design for an exercise garment, as shown and described.

DESCRIPTION

FIG. 1 is a front perspective view of an exercise garment showing my new design.

FIG. 2 is a rear perspective view thereof.

FIG. 3 is a front view thereof.

FIG. 4 is a rear view thereof.

FIG. 5 is a right plan view thereof.

FIG. 6 is a left plan view thereof.

FIG. 7 is a top view thereof.

FIG. 8 is a bottom view thereof.

FIG. 9 is a front perspective view thereof in an alternate position of use.

FIG. 10 is a rear perspective view thereof in an alternate position of use.

FIG. 11 is a front view thereof in an alternate position of use.

FIG. 12 is a rear view thereof in an alternate position of use.

FIG. 13 is a right plan view thereof in an alternate position of use.

FIG. 14 is a top view thereof in an alternate position of use.

FIG. 15 is a front perspective view thereof in a second alternate position of use.

FIG. 16 is a rear perspective view thereof in a second alternate position of use.

FIG. 17 is a top view of a second embodiment thereof.

FIG. 18 is a front perspective view of a second embodiment thereof; and,

FIG. 19 is a right plan view of a second embodiment thereof. The broken lines on the shaded area represent stitching, which does form a part of the claimed design. All other broken lines depict portions of the exercise garment that form no part of the claimed design.
